UNITED STATES PATENT OFFICE.

ROBERT W. SCOTT, OF LEEDS POINT, NEW JERSEY, ASSIGNOR, BY DIRECT AND MESNE ASSIGNMENTS, TO SCOTT & WILLIAMS, INCORPORATED, OF CAMDEN, NEW JERSEY, A CORPORATION OF NEW JERSEY.

PROJECTILE.

1,012,455.

Specification of Letters Patent. Patented Dec. 19, 1911.

Application filed July 6, 1909. Serial No. 506,101.

To all whom it may concern:

Be it known that I, ROBERT W. SCOTT, a citizen of the United States, residing in Leeds Point, Atlantic county, New Jersey, 5 have invented certain Improvements in Projectiles, of which the following is a specification.

My invention relates to that class of projectiles in which a mantle of relatively hard 10 metal envelops a dense and heavier core of softer metal, the object of the mantle being to secure penetration, to maintain true flight, to prevent deformation of the true form of the projectile, to produce a clean wound, 15 and to cause the desired rotation of the projectile in its passage through the barrel of the fire-arm by reason of the presence of a relatively hard metal for engagement with the rifling of the barrel. Ordinarily, the 20 mantle covers the softer metal core from tip to base, but in Letters Patent No. 733,920, granted to me on the 14th day of July, 1903, I described a projectile having a mantle which was discontinued some distance in advance of the base of the soft metal core, the object being to provide the harder metal 25 for engaging the rifling and imparting rotating movement of the projectile together with an exposure of the soft metal core at 30 the base of the projectile and beyond the rear end of the mantle where it could be expanded by the pressure of the exploding gases so as to serve as a check to prevent escape of gas between the projectile and the 35 barrel before the inertia of the projectile was overcome.

In the patented projectile that portion of the soft metal core which projected behind the harder metal mantle simply acted 40 as a follower and performed no function in effecting the rotation of the projectile by engagement with the rifling of the barrel, such rotation being caused wholly by the engagement of the rifling with the hard 45 metal mantle.

In projectiles intended for use in that class of fire-arms in which the projectile has not such a high velocity as that contemplated in the case of the patented projectile, such, for instance, as ordinary pistols and revolvers, that portion of the soft metal core which projects beyond the rear 50 of the mantle may be caused to act not only

as a gas check but also as a means of relieving the mantle either wholly or in part from 55 its duty of causing rotating movement to the projectile, and it is to projectiles of the latter class that my present invention relates.

In the accompanying drawing Figures 1, 60 2 and 3 are exaggerated sectional views illustrating different projectiles embodying my invention.

In the drawings, 1 represents the soft metal body or core of the projectile and 2 65 the mantle of harder metal with which the forward portion of said soft metal body or core is provided.

In the projectile shown in Fig. 1 the mantle has a cannelure 3 adapted to a recess in 70 the soft metal core so as to prevent any accidental removal of the mantle from the core, and in the rear of this cannelure the mantle is flared outwardly as at 4, so that while the forward portion of the mantle 75 only fills the barrel between the inner faces of the lands of the rifling the base of the mantle is of such a diameter as to reach the bottoms of the grooves of said rifling, and the projecting rear portion 5 of the soft 80 metal core is of the same diameter. When this projectile is fired there is a certain longitudinal upsetting of the soft metal core due to the pressure of the gases of explosion against the rear end of the same, and this 85 will be attended by an expansion of the flaring rear portion 4 of the mantle 2, so that the rifling will be engaged not only by the projecting body of soft metal at the rear 90 of the projectile but also by more or less of the rear portion of the harder metal 95 mantle and the rotation of the projectile will be due to the action of the rifling upon these two different metallic bodies, the expansion of the soft metal base of the projectile also causing it to serve as a gas check as in my patented projectile before alluded to. Owing to the limited area of the mantle in contact with the rifling, and to the fact that such contact portion is readily collapsible, no undue wear of the rifling will result.

Instead of providing the mantle with a flaring rear end to be expanded by the pressure of the soft metal core thereon when the projectile is fired, said mantle may, in the 105 first instance, be expanded for a certain

distance in advance of its rear end, as shown at 6 in Fig. 2, to provide a portion for engaging the rifling, this enlargement being also collapsible because of the absence of 5 any internal stiffening rib or flange thereon.

In some classes of projectiles the mantle may, throughout its entire length, be of such a diameter as not to engage the rifling, such a projectile being shown in Fig. 3. The rotation of this projectile is due entirely to 10 the action of the rifling upon the rear portion of the soft metal core which is of sufficiently greater diameter than the mantle to insure such engagement, and is preferably so formed at the front end as to present 15 a beveled shoulder 9.

It is important that the mantle shall be imperforate for the impact of the projectile 20 and the shock of explosion causes upsetting and lateral expansion of the soft metal core, and where the mantle covers only so much of the core as it does in the present form of projectile this upsetting action would cause the soft metal core to emerge to a greater or 25 less extent from any perforations in the mantle, thus forming studs, burs, or fins upon the outside of the mantle which would cause erratic flight, and interfere with the penetration of the projectile and would result 30 in the production of ragged wounds. In order to prevent the formation, from the same cause, of any fin at the junction of the base of the mantle and the forward portion of the projecting soft metal rear of the projectile, I prefer to chamfer the inner side of 35 the mantle at the base, as shown at 7, whereby the tendency of a bodily forward movement of the rear portion of the soft metal core is to force the metal inwardly instead of 40 outwardly.

I claim:

1. A projectile having a soft metal core and an imperforate mantle of harder metal discontinued in advance of the rear end of 45 said core, said mantle having a tapering nose, and, in the rear of the same, a straight portion of such diameter that it will not engage the rifling of the barrel, that portion of the core in the rear of the mantle being

of such diameter as to engage the rifling and 50 rotate or aid in rotating the projectile.

2. A projectile having a soft metal core and a mantle of harder metal, said mantle having a tapering nose, and, in the rear of the same, a straight portion of such diameter 55 that it will not engage the rifling of the barrel, the rear portion of the mantle being expanded so as to cause such engagement and the soft metal core providing an unyielding support for said expanded portion of the 60 mantle.

3. A projectile having a soft metal core and a mantle of harder metal having a tapering nose, and a straight portion in the rear of the same of such diameter that it 65 does not engage the rifling of the barrel, the mantle having a flaring base portion for engaging the rifling and the soft metal core providing an unyielding bearing for said flaring base or mantle. 70

4. A projectile having a soft metal core and a mantle of harder metal having a flaring base portion, and a cannelure in advance of said flare.

5. A projectile having a soft metal core 75 and a mantle of harder metal whose forward portion does not engage the rifling, said mantle being expanded at the base so as to effect such engagement, and the soft metal core being continued rearwardly beyond the 80 base of the mantle and serving also to engage the rifling, whereby the rotation of the projectile is due to such joint engagement.

6. A projectile having a soft metal core and a mantle of harder metal discontinued 85 in advance of the base of the core, said exposed portion of the core having at its forward end a beveled shoulder whose outer portion is flush with the sides of the following portion of the core. 90

In testimony whereof, I have signed my name to this specification, in the presence of two subscribing witnesses.

ROBERT W. SCOTT.
